Primary Examiner — T Chase Nelson*(74) Attorney, Agent, or Firm* — Joseph G Swan, PC(57) **CLAIM**

The ornamental design for a shoe bottom, as shown and described.

DESCRIPTION

The sole FIGURE is a plan view of the shoe bottom. The portions shown in broken lines are solely for the purpose of illustrating context, environment or other unclaimed areas and form no part of the claimed design. The claimed design is intended to encompass a first embodiment of a shoe bottom as illustrated in the drawing, as well as a second embodiment for the opposite matching shoe bottom, i.e., the mirror image of that shown.
